ADJUSTABLE FORM

Samuel I. Bush, Manassas, Va.

Application May 21, 1934, Serial No. 726,786

14 Claims. (Cl. 25—131)

This invention relates to adjustable forms and has for its object the production of a simple and efficient form which may be adjusted and positioned for forming various constructions, such as walls, ceilings, stairways, and other parts of buildings to be formed of plastic material.

A further object of this invention is the provision of a simple and efficient device which may be used in the construction of forms as well as the support of scaffolds and the like, and by means of which the large waste of lumber commonly necessary and the loss of time in cutting and fitting the lumber may be greatly reduced and in many instances entirely eliminated.

A still further object of this invention is the production of a simple and efficient frame comprising longitudinally extending interlocking members which may be connected or braced together by means of adjustable transversely extending connecting and bracing members.

A still further object of this invention is the production of a simple and efficient adjustable brace of a turnbuckle type, the parts of which are standardized so as to permit the same to be interchanged so as to allow the assembly of the various parts and the use of the various parts in many different combinations.

Other objects and advantages of the present invention will appear throughout the following specification and claims.

In the drawings:

Figure 1 is a plan view of a part of a form constructed in accordance with the present invention;

Figure 2 is a section taken on line 2—2 of Figure 1;

Figure 3 is a perspective view partly in section of one of the longitudinal frame members;

Figure 4 is a perspective view of a portion of the brace member, various parts being shown drawn apart;

Figure 5 is a detail perspective of one of the washer plates;

Figure 6 is a longitudinal sectional view through one end of the adjustable turnbuckle device;

Figure 7 is a vertical sectional view through a portion of the upper end of one of the longitudinal frame members;

Figure 8 is a section taken on line 8—8 of Figure 7;

Figure 9 is a sectional perspective view of the lower end of one of the longitudinal or elongated frame members;

Figure 10 is a transverse sectional view through

one of the elongated frame members showing the manner of connecting one of the clamping yokes to one of the elongated frame members;

Figure 11 is a side elevation of one assembly of the turnbuckle brace illustrating the manner of bracing the corner of a mold, the same manner being employed for supporting a scaffold;

Figure 12 is a front elevation illustrating the manner of clamping and connecting two abutting ends of the elongated frame members together;

Figure 13 is a section taken on the line 13—13 of Figure 12;

Figure 14 is a transverse sectional view taken on line 14—14 of Figure 12;

Figure 15 is a perspective view of one of the clamping plates;

Figure 16 is a front elevation of a portion of one end of one of the elongated frame members illustrating the upper end thereof and the manner of anchoring and connecting a right-angularly extending frame member thereto;

Figure 17 is a section taken on line 17—17 of Figure 16;

Figure 18 is a vertical sectional view illustrating the manner of attaching a vertically extending elongated frame member to a transversely extending elongated frame member running at right angles thereto and employing the connecting plate shown in Figure 15;

Figure 19 is a side elevation illustrating one type of assembly of the various parts and disclosing the manner in which the turnbuckle members may be used in connection with the elongated frame members for supporting or bracing one end of the turnbuckle members lying across the upper end of one of the elongated frame members; and

Figure 20 is a section taken on line 20—20 of Figure 19.

By referring to the drawings, it will be seen that I preferably employ a plurality of elongated frame members 10, which frame members may be interlocked or connected at their abutting ends to provide a form or frame of suitable length. These elongated frame members 10 are preferably of the same length to provide standard sections, each section having dove-tail notches 11 formed in their respective ends, the dove-tail notches 11 in one section being adapted to interlock with the adjoining section. By particularly considering Figures 3, 7 and 9, the particular type of dove-tail notches 11 will be noted, these notches being formed upon the inner face of the members 10 and along the inner faces of the longitudinally extending channels 13 formed in one end of the

member 10, the opposite end having the dove-tail notches 11 formed in the reverse faces to provide a proper and efficient interlocking joint.

Each elongated frame member 10 preferably comprises a pair of parallel angle-like ribs 14 which are connected at spaced intervals by means of integrally connecting webs 15 for dividing each elongated frame member 10 with end channels 13 and a central channel 16. Within each end channel 13 of the members 10 is pivotally secured a threaded nut 17, the nut 17 being journaled upon the supporting pins 18.

When the elongated frame members 10 are assembled to extend in vertical alignment for supporting a ceiling, scaffold, or other similar construction, it is preferable that the members 10, as shown in Figures 12 and 13 be braced at their interlocking joint connection by means of a flat bracing plate 19, the plate fitting flat against one side of the members 10 and spanning the connecting dove-tail joint 11. This plate is preferably wider than the width of the members 10, as shown in Figure 12 and carries a plurality of headed bolts 20 which extend through the apertures 21 of the plate 19, nuts 22 being threaded upon the headed bolts 20. The headed bolts are adapted to overhang the side edges of the members 10, as shown in Figure 12.

If desired, a clamping yoke 23 may be secured at the point of junction between the aligned frame members, the yoke 23 being provided with a threaded stem 24 which may extend through the channels 13 and pass through the apertures 25 formed in the plate and receive a nut 26 for holding the clamping yoke in position. This clamping yoke 23 carries at its outer end a pivot head block 27 which head block 27 is provided with a threaded aperture 28 extending longitudinally thereof, the head block 27 being also provided with laterally extending flanges 29 which extend at right angles to the side arms 30 of the clamping yoke 23. A threaded rod 31 may be threaded into the aperture 28 for the purpose of facilitating the connection of a transverse brace. As is shown in Figures 4 and 14, the threaded rod 31 is of a standard type, this type of rod being duplicated in many instances in order to provide interfitting connection in various assemblies. The rod 31 is provided with bifurcated ends 32 and the head block 27 is provided with an aperture 33 for receiving a locking pin 34, which pin 34 is adapted to fit into the aperture 33 and interlock with one of the bifurcated ends 32 and hold the rod 31 against rotation after it has once been adjusted. The manner in which this pin 34 engages the bifurcated ends 32 of the rod 31 will be clearly understood by considering Figure 6. This clamping yoke 23 may be used in various ways and for the purpose of forming a connection with one of the elongated frame members 10, the yoke 10 may be positioned as is shown in Figure 10 so as to allow the extension flanges 29 to overhang the edges of the centrally located apertures or slots formed in the elongated members 10, as shown in Figure 10. The yoke member 23 is of sufficient width to normally overhang the edges of the elongated members, as is shown in Figure 14, but when turned at right angles to this position, such as is shown in Figure 10, may easily slide through these apertures, Figure 10 being an enlarged view for the purpose of illustration. For this reason, the head block 27 is provided with flanges 29 for the purpose of engaging or overhanging the edges of the longitudinally extending slots formed in the elongated

members 10. If desired, in the assembly shown in Figure 10, washer plates 35 may be placed upon the threaded shank 24, these washer plates 35 having shoulder portions 36 formed thereon, and also having concave inner faces 37. A detail of one of these plates is shown in Figure 5. This plate may be used in the assembly such as is shown in Figures 1 and 2 when desired, the shoulders 36 being adapted to engage the inner faces of the angle-like rails 14 and act as a support for the threaded shank 24, as shown.

In assembling the bracing member, which is of a turnbuckle type, the yoke members 23 may be employed and support the rods 31 previously described. These rods 31 in turn are threaded into internally threaded sleeves 38 and the sleeves 38 are provided with apertures 39 near their ends for receiving pins 40 which pins are adapted to fit into and engage the bifurcated ends 32 of the threaded rods 31, thereby holding these rods in an adjusted position. Preferably two of these yoke members 23 and connecting rods 31 are employed with suitable sleeves 38, such as are shown in the assembled illustration in Figure 11, and these sleeves 38 are connected by means of a threaded turnbuckle rod 41, which turnbuckle rod 41 is oppositely threaded at its respective ends being threaded into the sleeves 38 for the purpose of drawing these sleeves toward each other or spreading the same apart, depending upon the direction in which the turnbuckle rod 41 is rotated. A central aperture 42 is formed in the turnbuckle rod 41 to facilitate the insertion of an operating rod or bar. From the foregoing description it will be seen that in the type shown in Figure 1, as well as in Figure 11, this turnbuckle member may be spread apart or drawn together to properly adjust and brace a mold or other framework. In the structure shown in Figure 11 illustrating the corner brace, I preferably employ two of these turnbuckle members, one extending in a vertical position as shown, and the other extending at an angle of approximately forty-five degrees. The position of these braces or turnbuckle members may be varied depending upon the character of the work, and the type of assembly desired.

By considering Figures 16 and 17 one form of the assembly is illustrated, disclosing the manner of attaching two of the elongated frame members together to form a convenient connection by utilizing the pivotally connected nuts 17 described above. These nuts 17 are as previously described, pivotally connected within the channels 13 and when the elongated frame members 10 are assembled, as shown in Figures 16 and 17, an anchoring bolt 43 is employed having a threaded lower end 44 and a reduced unthreaded shank 45 adjacent its head 46. In this way, the bolt 43 may be threaded through the upper nut 17, such as shown in Figure 17, until the reduced extension 45 is brought into registration with the threaded opening in the nut 17. The bolt 43 may then freely rotate in the upper nut for the purpose of permitting a proper threading engagement with the lower nut 17 carried by the right angularly extending elongated frame member. The head 46 is adapted to overhang the horizontally extending frame member 10 so as to provide a firm joint connection.

A further assembly is illustrated in Figure 18, wherein a vertical elongated frame member 10 engages a horizontally extending frame member 10 which is supported intermediate its ends. The bracing plate 19 previously described may

be used in this assembly as illustrated, and the bolt 43 previously described may be extended through the horizontally extending elongated frame member 10 so as to allow the lower threaded portion 44 of the bolt 43 to engage the nut 17 carried by the vertically extending elongated frame member 10. The head 46 of the bolt 43 may be of a greater width than the channels 13 and 16 of the frame member 10, to permit the head 46 to overhang the sides of the channels. The bolts 20 firmly grip the horizontal frame member 10 and hold the horizontal frame member 10 against longitudinal shifting, thereby relieving strain from the head 46 of the bolt 34.

As shown in Figures 19 and 20 a further assembled view is illustrated disclosing two of the bracing members of the turnbuckle type mounted in conjunction with the vertically extending elongated frame member 10. One of the washer plates 35 previously described is used in this assembly, the concave portion 37 thereof constituting a cradle for supporting the threaded turnbuckle pin 41 as illustrated, the anchoring bolt 43 being employed in this assembly and extending through the aperture 42. From the foregoing description it will be seen that a very simple and efficient arrangement has been provided for assembling forms of various types, supporting scaffolding, and in fact in providing a form for many types of building structure eliminating the necessity of the cutting and wasting of lumber.

The important part of the present invention is the structure of the elements going to make up this assembly, and it is not desired to limit this invention to any particular method of assembly.

It should be understood that certain detail changes in the mechanical construction, combination and arrangement of parts may be employed without departing from the spirit of the invention so long as these changes fall within the scope of the appended claims.

Having described the invention, what is claimed as new is:—

1. An adjustable form and the like comprising elongated frame members having longitudinally extending openings formed throughout the length thereof, yoke members adapted to engage said frame members and extend through said openings, means for clamping the yoke members upon said frame members, adjustable expansion means detachably engaging the yoke members, and means for pivotally connecting the adjustable expansion means to said yoke members.

2. An adjustable frame for use in constructing forms, scaffolds, and the like, comprising a plurality of elongated members, adjustable bracing members adapted to be located intermediate the elongated frame members, yoke members slidably mounted upon the frame members and extending therethrough, means for clamping the yoke members in an adjusted position, each yoke member provided with a pivoted supporting head, and adjustable means adapted to engage the pivoted supporting heads of said yoke members for connecting said expandable brace members to said yoke members.

3. An expandable bracing member comprising a plurality of internally threaded sleeves, an intermediate threading member engaging said sleeves having the ends thereof threaded in opposite directions for drawing said sleeves together or spreading the same apart as said intermediate member is rotated in a selected direction, re-

movable threaded rods threaded into the outer extremities of said sleeves, anchoring yoke members, pivoted heads carried by said yoke members, and said last mentioned rods being threaded into said pivoted heads.

4. An expandable bracing member comprising a plurality of internally threaded sleeves, an intermediate expandable threading member engaging said sleeves having the ends thereof threaded in opposite directions for drawing said sleeves together or spreading the same apart as said intermediate member is rotated in a selected direction, removable threaded rods threaded into the outer extremities of said sleeves, anchoring yoke members, pivoted heads carried by said yoke members, said last mentioned rods being threaded into said pivoted heads, and said heads having means for engaging said last mentioned rods for locking said last mentioned rods against accidental rotation.

5. An expandable bracing member comprising a plurality of internally threaded sleeves, an intermediate expandable threading member engaging said sleeves having the ends thereof threaded in opposite directions for drawing said sleeves together or spreading the same apart as said intermediate member is rotated in a selected direction, removable threaded rods threaded into the outer extremities of said sleeves, anchoring yoke members, pivoted heads carried by said yoke members, said last mentioned rods being threaded into said pivoted heads, said pins having notched ends, removable rods engaging said pivoted heads for fitting into said notches and locking said rods against rotation with respect to said head, and pins carried by said sleeves for similarly engaging opposite ends of said rods.

6. An expandable bracing member comprising a plurality of internally threaded sleeves, an intermediate expandable threading member engaging said sleeves having the ends thereof threaded in opposite directions for drawing said sleeves together or spreading the same apart as said intermediate member is rotated in a selected direction, removable threaded rods threaded into the outer extremities of said sleeves, anchoring yoke members, pivoted heads carried by said yoke members, said last mentioned rods being threaded into said pivoted heads, and said heads having laterally extending shoulders to constitute abutments to facilitate the supporting of said heads and yokes in a clamped position.

7. An expandable bracing member comprising a plurality of internally threaded sleeves, an intermediate threading member engaging said sleeves having the ends thereof threaded in opposite directions for drawing said sleeves together or spreading the same apart as said intermediate member is rotated in a selected direction, removable threaded rods threaded into the outer extremities of said sleeves, anchoring yoke members, pivoted heads carried by said yoke members, said last mentioned rods being threaded into said pivoted heads, each yoke having a threaded extension rod, a nut threaded on said threaded extension rod, and the yoke being of substantial width to constitute an abutment shoulder at the point of junction of said threaded rod with said yoke.

8. In combination with a plurality of elongated frame members having elongated openings formed therein, yoke members having threaded extensions projecting through said openings, washer plates fitted upon said threaded extensions, and having shoulders adapted to fit within said elongated openings.

gated openings, clamping nuts for clamping said washer plates in position, said yoke members being of greater width than said openings for overhanging the side edges of said openings, and pivotally mounted heads carried by said yoke members.

9. In combination with a plurality of elongated frame members having elongated openings formed therein, yoke members having threaded extensions projecting through said openings, washer plates fitted upon said threaded extensions and having shoulders adapted to fit within said elongated openings, clamping nuts for clamping said washer plates in position, said yoke members being of greater width than said openings for overhanging the side edges of said openings, pivotally mounted heads carried by said yoke members, said yoke members being sufficiently narrow when turned in one direction to extend through said openings in said frame members, and said heads having overhanging flanges of sufficient width to overhang the side edges of the elongated openings of said frame members when said yoke member extends through said openings.

10. A frame of the class described comprising a plurality of frame members of a substantially angle-beam structure, the angle-beams being integrally connected at spaced intervals to provide elongated openings at the ends and intermediate the ends of the frame members, internally threaded members being journaled for rotary movement in the ends of said frame members, and threaded bolts extending through the internally threaded members of adjoining frame members for locking the frame members together.

11. A frame of the class described comprising a plurality of frame members having openings formed therein, an internally threaded pivoted nut carried near each end of each frame member, a threaded bolt having a head and a reduced shank near one end, the reduced shank being adapted to extend through the opening formed in one frame member to permit the engagement with the threaded nut in an adjoining member to provide a clamping locking engagement between two adjoining members.

12. A frame of the class described comprising a plurality of frame members having openings formed therein, an internally threaded pivoted nut carried near each end of each frame member, a threaded bolt having an enlarged head and a reduced shank near one end, the reduced shank being adapted to extend through the opening formed in one frame member to permit the engagement with the threaded nut in an adjoining member to provide a clamping locking engagement between two adjoining members, the head of the bolt being of greater width than the width of the opening formed in the frame member, an abutting supporting plate adapted to engage one member and support an adjoining member, and clamping bolts carried by the plate for anchoring the plate in engagement with one of the frame members, and holding the frame member against lateral shifting.

13. A frame of the class described comprising a plurality of elongated frame members having interlocking dove-tail notches formed in their overlapping adjacent faces to prevent longitudinal relative movement and permit lateral displacement, a bracing plate adapted to span the joint between two abutting frame members, a brace connection carried by the plate and extending through the frame members, and headed bolts carried by the plate and overhanging the frame members for locking said bracing plate in engagement with the frame members.

14. In combination with an elongated frame member, a cradle plate supported upon one end of said frame member and having a concave upper face, a threaded nut secured near the upper end of said frame member, a locking bolt, an expandable brace lying within said concave face of said cradle member, said locking bolt passing through said expandable brace and engaging said nut, and an expandable brace anchored upon said frame member and engaging the outer end of said first mentioned expandable brace.

SAMUEL I. BUSH. 45
